[57] **CLAIM**

The ornamental design for a anemometer/hygrometer instrument, as shown and described.

DESCRIPTION

FIG. 1 is a perspective view of a Anemometer/Hygrometer instrument, having the first embodiment of our new design; FIG. 2 is a left side view of the Anemometer/Hygrometer instrument of FIG. 1 having a bendable column which bends in both directions;

FIG. 3 is a left side view of the Anemometer/Hygrometer instrument of FIG. 1 illustrating a tilting head in the tilted position;

FIG. 4 is a top view of the Anemometer/Hygrometer instrument of FIG. 1;

FIG. 5 is a right side view of the Anemometer/Hygrometer instrument of FIG. 1 having a bendable column which bends in both directions;

FIG. 6 is a right side view of the Anemometer/Hygrometer instrument of FIG. 1 illustrating a tilting head in the tilted position and extended column;

FIG. 7 is a bottom plan of the Anemometer/Hygrometer instrument of FIG. 1;

FIG. 8 is a front view of the Anemometer/Hygrometer instrument of FIG. 1;

FIG. 9 is a rear view of the Anemometer/Hygrometer instrument of FIG. 1.

FIG. 10 is a perspective view of the Anemometer/Hygrometer instrument having the second embodiment of our new design;

FIG. 11 is a left side view of the Anemometer/hygrometer instrument of FIG. 10 illustrating a tilting a head in the tilted position;

FIG. 12 is a right side view of the Anemometer/Hygrometer instrument of FIG. 10 illustrating a tilting head in the tilted position;

FIG. 13 is a top plan of the Anemometer/Hygrometer instrument of FIG. 10;

FIG. 14 is a rear view of the Anemometer/Hygrometer instrument of FIG. 10;

FIG. 15 is a front view of the Anemometer/Hygrometer instrument of FIG. 10; and,

FIG. 16 is a bottom plan of the Anemometer/Hygrometer instrument of FIG. 10.
